UNITED STATES PATENT OFFICE.

ELMER L. OGLE, OF CHICAGO, ILLINOIS, ASSIGNOR TO FEDERAL SIGN SYSTEM (ELECTRIC), OF NEW YORK, N. Y., A CORPORATION OF NEW YORK.

ELECTRIC FUSE.

1,276,800.

Specification of Letters Patent. Patented Aug. 27, 1918.

Application filed April 23, 1917. Serial No. 163,811.

To all whom it may concern:

Be it known that I, ELMER L. OGLE, a citizen of the United States, residing at Chicago, in the county of Cook and State of Illinois, have invented a certain new and useful Improvement in Electric Fuses, of which the following is a specification.

My invention relates to electric fuses or cutouts and the general object of the invention is to simplify devices of this character so that the manufacture may be facilitated, the number of parts reduced to a minimum and the durability brought to a maximum. My present improvements are concerned 15 more particularly with the elements which form the end closures of the inner and outer tubes or casings.

I accomplish the objects by the mechanism illustrated in the accompanying drawings, 20 in which:

Figure 1 is a longitudinal section of a device embodying my invention.

Fig. 2 is an end view partly in section looking toward the left in Fig. 1.

Fig. 3 is a sectional view on the line 3—3, Fig. 1.

Fig. 4 is a sectional view on the line 4—4, Fig. 1.

Fig. 5 is a perspective of the end cover for 30 one end of the device.

Fig. 6 is a perspective of the ferrule which coöperates with the end cover shown in Fig. 5, and

Fig. 7 is a fragmentary side view partly 35 in section showing the assembly of one of the end caps, star washers and associated parts.

Similar numerals refer to similar parts throughout the views.

In the form chosen to explain the nature 40 of the invention, the fusible element 1 is embedded in suitable filling material 2. This is inclosed within a tube 3 of paper or other insulating material. The tube and its contents are inclosed within a casing 4 which, at the left end (Fig. 1), is closed by an end cap 5 of any suitable construction. At the opposite end the casing 4 has a ferrule 6 which is shown in perspective in Fig. 6, and 45 which embodies one of the elements of the invention. This ferrule may be secured to the casing in any suitable manner, for example, by indenting the metal into the casing as illustrated at 7, Fig. 1. This ferrule

is open at the end so that the tube 3 can be 55 slipped into it when the device is being assembled, but has an inwardly extending flange 9 adapted to engage and overlie the edge 10 of the end cover 11, shown in perspective in Fig. 5. In the best form, flange 60 9 extends throughout one-half of the circumference of the ferrule and has opposite to it a notch or countersink 12 which accommodates the fusible element 1, which is led out around the end of the casing and 65 terminates in an end piece 13. As well shown in Fig. 6, the metal of the ferrule is cut back or countersunk at that portion which is not occupied by the flange 9. It is 70 cut back about the thickness of the cover to form a seat for said cover and permit it to lie at right angles to the axis of the device. This results in the formation of the shoulders 16, hereinafter mentioned. The 75 cover 11 is circular to fit the end of the ferrule and has two shoulders 15 which abut the end 16 of the ferrule and thus make a tight closure. The cover has an integral lug 18 which extends down the side of the device over the end piece 13 of the fuse. It 80 has an aperture 19 which registers with an aperture 20 in end piece 13 and these both register with an aperture 21 formed in the side of the ferrule. A boss 22 is formed on the inside of the ferrule which sinks into 85 the side of the casing 4 and helps hold the ferrule securely in position upon the casing. Boss 22 is internally threaded to take the screw 23. It will be evident that when the parts are assembled as shown in Fig. 1 and 90 screw 23 is in place, not only will the fuse be put into good electrical contact with both the ferrule and the cover, but the cover will be securely held in place. The screw prevents the cover from becoming dislodged 95 from under the flange 9 of the ferrule and hence, by the aid of this single screw both the electrical contact is made and the cover is assured of maintaining its position. Flange 9 protects the cover from blows from 100 external objects and in addition, the appearance of the device is improved. The entire end area of the device, that is, the entire area of the cover part proper is plain and free from screws or other attaching devices. 105

Now referring to another feature of construction by which the device is improved: The insulating tube 3, which usually con-

sists of paper or similar material receives at each end a member which, for identification, may be referred to as a "star washer" 25, 26. While these operate upon the same principle, they are slightly different in form at the two ends of the device and hence will be referred to separately. The washer 25, shown at the right end of Fig. 1, is slotted to pass the fuse 1. It consists of a plate 10 which is of such size as to substantially close the end of the tube and retain the filling material in place within the tube. It has a number of points 27 formed upon it and these are sharp enough to sink into the 15 material of the tube when the latter is forced down upon it. This occurs when the end cap 28 is clenched over the end of the tube. It is slotted to pass the fusible element. This end cap is clenched or crimped onto the 20 end of the tube and crushes it enough to force it onto the point of the star washer. In small size fuses, where the paper composing the inner tube is thin, difficulty has been experienced in providing means where- 25 by the end cap may be secured. The tube is not stiff enough to retain the cap and consequently frequently lets the cap become loosened. With my construction, however, the star washer forms an internal backing 30 for the tube and prevents it from yielding or crushing when the clenching pressure is applied to the cap. In my construction, the star washer not only forms the backing to resist pressure from the outside but, when 35 the parts are assembled under the conditions mentioned, the washer itself, having its points sunk into the material of the tube, is rigidly held and hence forms a closure for retaining the filler.

40 The star washer 26 at the opposite end of the device operates in the same manner and so also does the companion end cap 30. This washer and end cap, however, have larger central openings, as they are designed 45 to pass the socket 31 which supports the adjacent end of the fusible element. Said socket is internally threaded to take the tube 32. The head of this screw enters a countersink 33 in the end cap 5 and holds the

parts assembled as shown at the left end of 50 Fig. 1.

From the foregoing it will be seen that I have improved the end closure of both the outer casing and the inner tube. A single screw is sufficient to both obtain contact and 55 to retain the end closure at the end of the casing. As to the inner tube, the star washers form a backing to brace the material when the end caps are being clenched into place and they also contribute to holding 60 the filling material in position.

The parts are simple in form and easy to manufacture and assemble, and when assembled, produce both an inner end and an outer closure which is sure and effective. 65

Having thus described my invention, what I claim as new and desire to secure by Letters Patent, is:

1. An electric fuse having a fusible element, a casing, an end cap for the casing, 70 means for connecting the fusible element to the cap, said means including a metallic tube, into the end of which the end of the fusible element is inserted, the tube being collapsed and pressed onto the fusible ele- 75 ment to securely grip it, and means for fastening said tube to said end cap.

2. An electric fuse having a fusible element, a casing, an end cap for the casing, a metallic tube, one end of which is firmly 80 pressed onto the end of the fusible element to grip it, the opposite end of the tube being threaded, and a threaded element making screw connection with said tube and also making connection with and securing said 85 end cap.

3. An electric fuse having a casing, an end cap therefor, a fusible element, a metallic tube, one end of which contains and is collapsed onto to grip the fusible element, the 90 opposite end of the tube being cylindrical and internally threaded, and a screw passing through the end cap and screwing into said tube.

In witness whereof I have hereunto sub- 95 scribed my name.

ELMER L. OGLE.
